US00D861184S

(12) **United States Design Patent** (10) Patent No.: **US D861,184 S**
 Stern Hasemann et al. (45) Date of Patent: ** Sep. 24, 2019

(54) **POINT PRESSING TOOL**

(71) Applicants: **Jennifer Stern Hasemann**, Manchester, CT (US); **Daniel E. Tracy**, Cortland, NY (US)

(72) Inventors: **Jennifer Stern Hasemann**, Manchester, CT (US); **Daniel E. Tracy**, Cortland, NY (US)

(**) Term: **15 Years**

(21) Appl. No.: **29/654,433**

(22) Filed: **Jun. 25, 2018**

(51) LOC (12) Cl. **28-03**

(52) U.S. Cl.

USPC **D24/214**

(57) **CLAIM**

The ornamental design for a point pressing tool, as shown and described.

DESCRIPTION

FIG. 1 is a perspective top front right view of a point pressing tool, showing our new design;

FIG. 2 is a perspective top rear left view thereof;

FIG. 3 is a front elevation view thereof;

FIG. 4 is a rear elevation view thereof;

FIG. 5 is a left elevation view thereof;

FIG. 6 is a right elevation view thereof; and,

FIG. 7 is a top plan view thereof, wherein the bottom plan view is an identical image thereof.

1 Claim, 5 Drawing Sheets
